GOLFER'S ACCESSORY TOOL

Donald A. Johnson, Whittier, Calif.

Application February 27, 1956, Serial No. 40,362

Term of patent 7 years

(Cl. D34—5)

I claim:

The ornamental design for a golfer's accessory tool, substantially as shown.
